UNITED STATES PATENT OFFICE.

CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

INDEPENDENT-VOTING MECHANISM FOR VOTING-MACHINES.

No. 914,007.

Specification of Letters Patent. Patented March 2, 1909.

Application filed July 8, 1908. Serial No. 442,587.

To all whom it may concern:

Be it known that I, CHARLES C. ABBOTT, a citizen of the United States, residing at Pittsfield, county of Berkshire, State of Massachusetts, have invented a new and useful Independent-Voting Mechanism for Voting Machines, of which the following is a specification.

This invention relates to the independent 10 voting mechanism of voting machines, and has for its object to simplify and cheapen the construction, reduce the number of parts and to greatly improve the operation in use.

With these and other objects in view I 15 have devised the simple and novel independent voting mechanism which will be herein-after described and then specifically pointed out in the claims hereunto appended.

In the accompanying drawings forming a 20 part of this specification, similar reference characters denote the same parts in all of the views.

Figure 1 is a rear elevation partly broken away, the rolls being shown without paper, 25 the clutch members disengaged and one shutter shown in the closed position; Fig. 2 a detail view, the paper feed roll being in vertical section and the clutch members engaged; Fig. 3 a section on the line 3—3 in Figs. 1 and 30 2, looking in the direction of the arrows, windings of paper on the paper supply roll and paper receiving roll being indicated by dotted lines; Fig. 4 a detail sectional view on the line 4—4 in Fig. 1, looking in the direction of the arrows, the shutter being closed; Fig. 5 a detail elevation showing a shutter 35 in the open position; Fig. 6 a section on the line 6—6 in Fig. 5, looking in the direction of the arrows; Fig. 7 a detail rear elevation on an enlarged scale, the shutter being closed as in Fig. 1; Fig. 8 a detail elevation 40 the reverse of Fig. 7; Fig. 9 a detail view illustrating a modified form of actuating slide; Fig. 10 a detail side elevation of the 45 link; Fig. 11 a detail sectional view on an enlarged scale on the line 11—11 in Fig. 1, looking in the direction of the arrows; Fig. 12 an enlarged view of the independent voting 50 strip and illustrating the operation in connection therewith of the voting strip indicator; Fig. 13 a detail view on a smaller scale illustrating the pointed end of the independent voting strip; Fig. 14 a view corresponding with Fig. 1, illustrating a variant form of the

invention, certain of the parts being omitted 55 for the sake of clearness in illustration; Fig. 15 a detail view illustrating the operation of the modified form of clutch shifter; Fig. 16 a detail sectional view on the line 16—16 in Fig. 14, looking in the direction of the arrows; and Fig. 17 is a detail perspective on an enlarged scale, illustrating the operation of the retaining latch.

In this machine, the voting apertures extend vertically and the shutters are raised in 65 opening them to disclose the independent voting strip and lowered again to close the apertures.

10 denotes the front plate which is provided with voting apertures indicated by 11. 70

12 denotes the shutters which have beveled edges and slide in undercut ways in plates 13 on the inner side of the front plate.

17 (see dotted lines Fig. 3) denotes the independent voting strip which passes over a 75 backing plate 18 rigidly secured in place contiguous to the apertures.

19 denotes the paper supply roll whose journals 20 are adapted to move freely at right angles to the plane of rotation in elongated bearings 21 as the diameter of the winding of paper on the roll changes. 80

22 denotes the paper receiving roll whose journals 23 are adapted to move freely at right angles to the plane of rotation in elongated bearings 24 as the diameter of the winding of paper on the roll changes. These rolls are preferably made of tubing with hubs at the ends having reduced portions which form the journals. 90

25 denotes the paper feed roll. This roll comprises hubs 26 and 27 and a tube or shell 28 secured to the hubs, this structure being adopted in all of the rolls for the sake of lightness and providing ample strength. 95

• The independent voting strip passes from the supply roll over the backing plate and the independent votes are written upon the portion of the strip supported thereby. After passing the backing plate, the strip passes 100 partly around the feed roll and is wound upon the receiving roll. It should be noted that the winding of paper on the supply roll rests wholly upon the winding on the receiving roll, and that the entire weight of both 105 rolls and the windings thereon rests upon the feed roll which is carried by brackets. I thus dispense with pawls or other means for

preventing backward movement of the rolls and insure that neither roll will move to the slightest extent except when the receiving roll is driven by the feed roll, so that only the 5 exact amount of the independent voting strip wound on the receiving roll can be drawn from the supply roll. The hubs 26 and 27 of the feed roll are provided with journals 29 which are mounted in bearings 30 10 carried by brackets 31.

32 denotes the feed shaft which extends longitudinally of the feed roll, passes through hubs 26 and 27 without contact therewith, and is journaled in bearings 69.

15 33 denotes pinions on the feed shaft which engage racks 34 on bars 35 which reciprocate vertically and carry the closing bar 16. One end of hub 26 is provided with a clutch member 36 and just within the clutch member is 20 a groove 37 which receives the corresponding bearing 30, thereby locking the feed roll against endwise movement.

38 denotes a clutch sleeve which is keyed to the feed shaft so as to rotate therewith but 25 is free to slide longitudinally thereon. This sleeve is provided with a clutch member 39 which is adapted to engage clutch member 36 and with a groove 40 which is engaged by a yoke 42 on clutch shifter 41. One end of 30 the feed shaft is provided with a spiral gear 56 which meshes with a spiral gear 57 on a vertical shaft 58 which is rotated by means of intermediate connections (not shown) after the voting operation and in turn imparts rotation to the feed shaft.

It has been noted as an important feature 40 of the invention that the entire weight of the set of rolls and the windings of paper is carried by the bearings of the feed roll. It should furthermore be noted that the feed 45 shaft has no weight to carry, that it passes through the feed roll without contact therewith and is journaled independently thereof. This construction does away with unnecessary friction and wear and insures uniformity 50 and certainty of operation.

43 denotes the actuating slide which reciprocates in ways 44 on the outer face of the front plate and is covered and retained in 55 place by a plate 72 secured to the ways. The actuating slide carries a block 45 having an incline 46 and a widened U-shaped bracket 47, both of which extend through an opening 48 in the front plate. Incline 46 on block 45 60 is adapted to be engaged by a corresponding incline 49 on a block 50 (see dotted lines Fig. 1) carried by closing bar 16, the function being to move the actuating slide and the sliding clutch member from the position shown in Fig. 2 to the position shown in Fig. 1 when the parts are returned to their normal 65 position after an independent voting operation, as will be more fully explained. The clutch shifter is carried by the actuating slide. In order to provide a yielding connec-

tion between these parts, the clutch shifter is mounted to slide on a rod or pin 51 detachably secured to bracket 47 and is retained in operative position by a spring 51 surrounding the pin, one end of which bears against 70 the bracket and the other against the clutch shifter. When the sliding clutch member is moved to the engaging position, should the teeth not interlock, the spring will yield. As soon, however, as the feed shaft and sliding clutch member commence to rotate, the spring will cause the teeth on the sliding clutch member to engage the teeth of the fixed clutch member carried by the feed roll and will impart rotation thereto. In order 75 to prevent the clutch shifter from cramping in use, I provide the clutch shifter with an elongated bracket 53 which is rigidly secured thereto.

54 denotes a rod or pin detachably secured 80 to ears 55 themselves rigidly secured to the front plate. This rod passes freely through the ends of the bracket and the clutch shifter, thus providing a long bearing for the clutch shifter on the rod and permitting the shifter 90 to slide freely without cramping. Should the spring break, a new one may be put in place by simply removing pin 51 and without disturbing other parts.

A novel feature of the present machine is 95 that I provide means for insuring absolutely accurate tabulation of the independent votes even should the independent voting strip pass through the rolls slightly irregularly. It is found in practice that in large machines, 100 for example, in a thirty-key machine, so called, in which thirty offices may be voted for independently—it is difficult to tell for which office independent votes are cast. This may result from slight unevenness in 105 the movement of the independent voting strip and from the fact that the independent votes are irregularly written upon the strip at the apertures. This difficulty I wholly overcome in the manner which I will now describe. The feed roll is provided with two circumferential sets of holes or depressions indicated by 73. Operating in connection with these sets of holes I provide toothed wheels 74 which rotate on pins 75 in brackets 115 76 which are riveted to the front plate. These wheels are rotated by the feed roll and the teeth register with the holes and make a row of indentations or perforations, indicated by 77, in the independent voting strip. 120 In the present instance I have shown the toothed wheels and the holes in the feed roll so arranged as to make the indentations or perforations between the fifth and sixth and the twenty-fifth and twenty-sixth shutter 125 openings.

In connection with each machine I provide an independent voting strip indicator indicated by 78. This strip is provided with numerals 79 corresponding with the offices 130

to be voted for, in the present instance from one up to thirty, with cross lines 80 corresponding with the lines of indentations or perforations 77 in the voting strip and with 5 dots 81 to indicate the divisions of the office line. When the polls are closed the independent voting strip is removed from the machine and laid upon a table and indicator 78 is placed thereon with cross lines 80 registering with the lines of indentations or perforations in the strip, so that the tabulator can see at a glance for just what offices the votes on the independent voting strip have been cast, the indicator being moved along 10 on the strip until all the independent votes have been tabulated. For convenience in threading the independent voting strip into the machine, that is, passing it through the rolls, the end of the strip is pointed as at 82, 15 the pointed end being long enough to pass around the feed roll before coming in contact with the toothed wheels 74, so that these wheels will not interfere in the least with the operation of placing the paper in the machine.

As it is necessary that the supply roll be raised before the receiving roll can be removed from the machine, I provide swinging hooks 83 which are pivoted to any suitable 30 portion of the machine. These hooks are adapted to engage the journals 20 of the supply roll. In order to permit the removal of the receiving roll, the supply roll is raised, causing the journals thereof to engage the 35 undersides of the hooks and displace them, and when the journals have been raised past the hooks the latter will drop back to place automatically and support the supply roll by its journals in the raised position. In setting up the machine again, the supply roll is 40 raised off the hooks which are swung back out of the way and the supply roll is lowered to place, the hooks then dropping back to place again ready to support the supply roll 45 when it is again raised.

Each shutter is provided with an outwardly extending ear 84 lying in the corresponding aperture 11, for convenience in opening the shutter and with an inwardly extending 50 ear 59 which is adapted to be engaged by the closing bar to close all opened shutters should they not themselves drop to the closed position when the exit mechanism and intermediate connecting mechanism is operated after a voting operation.

60 denotes one of the interlocking members and 61 a link connected to the interlocking member and having at its upper end an inwardly projecting head 62 formed from 65 three plates of metal secured to the link by a rivet 85 elongated in cross section which locks the plates against turning. The outer plate is elongated and widened to form a lip 86 the purpose of which will presently be explained. The front plate is provided with

a series of openings 63 and the upper end of each way plate 13 is provided with a recess 68 which corresponds in shape with the lower portion of the corresponding opening 63 in the front plate. The upper portion of the 7 left side of each opening 63 consists of an incline 70, and the lower portion of the right side of said opening and the right side of recess 68 in the corresponding plate 13 consists of an incline 87. The functions of these inclines will presently be explained. Head 62 normally lies in the lower portion of opening 63 and in recess 68 and rests upon incline 87, the widened lip 86 of the outer plate of the head lying on the outer side of the front plate 80 and retaining the head securely in position, rendering it impossible for the head to jump out of place when traveling down the incline.

64 denotes openings in actuating slide 43 the right walls of which, indicated specifically by 71, engage the outer plates of the heads in the return movement as will be more fully explained. At the upper end of each shutter is a reduced portion 65 terminating in an incline 67. When a shutter 90 is in the closed position as in Figs. 1, 4 and 7, the head of the corresponding link is lying in the lower portion of opening 63 in the front plate and the recess 68 in the top of a way plate 13 and rests upon incline 87, as 95 clearly shown in Fig. 7, the underside of the inner plates of the heads being preferably beveled at the corners as shown in Figs. 7 to 10, inclusive, to form bearings on inclines 87 and 67. When a shutter is opened, 100 i. e., raised, the corresponding link 61 is raised through the engagement of the head 62 with the incline on the shutter and is caused to travel up incline 87 on the front plate and plate 13. As the head is moved 105 upward, the incline on the shutter forces the head against the right wall 71 of the corresponding opening 64 in the actuating slide and forces said slide toward the right, causing the clutch shifter to move the sliding 110 clutch member into engagement with the fixed clutch member on the end of the feed roll (see Figs. 1 and 2).

The movement of link 61 just described locks, i. e., takes the slack out of the interlocking member and locks that office line against regular voting. This renders it impossible for a voter to open a shutter far enough to write a name on the independent voting strip and then close the shutter and 115 vote regularly for the same candidate or another candidate for the same office.

66 denotes shoulders or lands formed by the upper ends of plates 13 and a corresponding horizontal portion of the walls of openings 63 in the front plate. After a head 62 has been raised into alignment with the corresponding shoulder or land by the opening of a shutter, further upward movement of the shutter will cause incline 67 on the 120 125 130

shutter to force the head over on the shoulder or land where it will remain, locking the link in the raised position and locking the interlocking member taut so that none of the 5 regular voting members (not shown) in that office line can be operated until the return movement of the actuating slide; that is the movement which disengages the clutch members and is produced by the closing bar 10 when a voter leaves the machine.

In use it will of course be understood that a voter may vote for an independent candidate for one or for any number of the offices to be voted for. The opening of the first 15 shutter actuates operating slide 43 and moves the clutch members into engagement. The opening of additional shutters has no effect upon the actuating slide but raises the corresponding links, forces the heads on 20 the links over upon the lands and locks the corresponding interlocking members rigidly so that regular votes cannot be cast for candidates for the same office.

It will be noted that the first portion of the 25 movement of a shutter for independent voting places the head of the link, which is connected to the corresponding interlocking member, upon the land, locking the interlocking member taut, so that it is rendered 30 impossible for a voter to partly raise a shutter, vote independently, push the shutter back and then vote regularly for the same or for another candidate for the same office. In other words, having decided to 35 vote independently for a certain office and partly opened the corresponding shutter, the voter is bound by his decision. In order to render it impossible for a voter, after having voted independently to close the 40 shutter, which I will term shutter No. 1, through whose aperture he has voted, then to open shutter No. 2 and by the insertion of an instrument through aperture No. 2 to force the head of the link 61 corresponding 45 to shutter No. 1 off from the corresponding land 66, so that the shutter will drop and the interlocking member be unlocked; then to vote for office No. 1 in the regular ballot; then to write a vote in aperture No. 2; then 50 to close shutter No. 2 and open shutter No. 3 and force the head of the link 61 corresponding to shutter No. 2 off from the corresponding land 66, and then to vote for office No. 2 in the regular ballot, and to repeat this 55 operation indefinitely, I provide each way plate 13 with a guard flange 88 which projects inward far enough to prevent an instrument from passing it.

In the modified form of actuating slide 60 illustrated in Fig. 9, the link is made slightly longer which carries the head higher and the openings 64 in the actuating slide are formed in the upper side of said slide instead of in the lower side as in the other form, the principle of operation being precisely the same.

After a voter has completed the voting operation, he actuates operating mechanism in leaving the machine, which, by means of intermediate connections (not shown), imparts rotation to shaft 58 and feed shaft 32. 70 If there has been no independent voting, the clutch members will not be in engagement and the rotation of the feed shaft will have no effect on the paper feed roll, which is supported in its bearings wholly independently 75 of the feed shaft. If there has been independent voting, the clutch members will have been placed in engagement by means of the actuating bar and the clutch shifter and the rotary movement of the feed shaft 80 will be imparted to the feed roll. The effect of this rotary movement of the feed roll, partly around which the independent voting strip passes, is to actuate the receiving roll through frictional contact therewith and to 85 actuate the supply roll through frictional contact with the receiving roll, the entire weight of both receiving and supply rolls and the windings of paper thereon being carried by the feed roll which in turn is carried 90 by bearings 30, there being no weight upon the feed shaft which is carried by bearings 69. The result is that while the independent voting strip is kept taut, there is no appreciable tension placed upon it. The required amount of paper is drawn from the supply roll and an equal amount is wound on the receiving roll each time the feed roll is actuated, the used portion of the strip being drawn from the backing plate and a fresh 100 portion thereof placed in position for the next independent voter. This construction causes the winding of the same amount of paper on the receiving roll each time the feed roll is actuated without regard to the size of 105 the windings on the supply roll and the receiving roll. As the diameter of the winding on the receiving roll increases, the journals of said roll will move freely in their bearings. Each time the feed shaft is operated after a 110 voting operation, through the engagement of pinions 33 with racks 34, closing bar 16 is moved downward into position to cause incline 49 on block 50 to engage incline 46 on block 45. If there has been no independent 115 voting, the parts will be in the position shown in Fig. 1, and there will be no engagement of the inclines. If there has been independent voting, the actuating slide and sliding clutch member will be in the position 120 shown in Fig. 2 and the engagement of the inclines on the blocks will move the actuating slide and sliding clutch member toward the left from the position shown in Fig. 2 to the position shown in Fig. 1. When the 125 parts are in the position shown in Figs. 2 and 5, movement of the actuating slide toward the left will cause walls 71 of openings 64 to engage the heads 62 (in the present instance lips 86) upon the links corresponding 130

with all opened shutters and will move said heads off from the shoulders or lands. As soon as a head has been forced off from a land, it will engage the incline 70 of opening 5 63 in the front plate, the action of which will be, should the link not drop of its own weight, to force the head downward into the lower portion of opening 63 in the front plate and recess 68 in the corresponding plate 13 10 to its normal position, that is, resting on the incline 87. The shutters ordinarily move easily enough in the ways so that they will drop from the open position as in Figs. 5 and 6 to the closed position as in Figs. 1 and 4. 15 Should the opened shutters not drop by gravity, however, they will be moved to the closed position through the engagement of the closing bar with ears 59. It should be noted that the downward movement of the 20 closing bar first insures the return of all opened shutters to the closed position so that the lower edges of the inclines 67 of opened shutters will be sure to have moved downward as far as the corresponding lands 25 at the instant incline 49 on cam block 50 comes in contact with incline 46 on cam block 45 and causes the return movement of the actuating slide. In other words, the inclines on the shutters will be below the heads 30 before the latter are forced off from the lands by the actuating slide.

In the modified form illustrated in Figs. 14 to 17, inclusive, spiral gears 56 and 57 and vertical shaft 58 have been placed at the 35 other end of the feed shaft, and the clutch mechanism likewise has been shifted to the opposite end of the paper feed roll from that shown in Fig. 1. Brackets 89 correspond with brackets 31 in the other form and the 40 fixed clutch member 90 corresponds with the other form. The sliding clutch member 91 is on a sleeve 92 which slides on the feed shaft and is provided with lugs or projections 93 which engage slots 94 on the hub 95 45 of one of the pinions 33. The sliding clutch member is provided with a groove 96 which is engaged by lugs 97 on a clutch shifter 98 pivoted on a bracket 99 which is riveted to the front plate of the machine. 100 denotes 50 a rod which is pivoted to the upper end of the clutch shifter and the opposite end of which passes through a lug 101 which extends from actuating slide 43 and projects through an opening 102 in the front plate. A spring 55 103 surrounding the rod bears against a collar 104 on the rod and against lug 101. 105 denotes a washer on the rod which lies between lug 101 and a pin 106 at the inner end of the rod. The action is substantially 60 the same as in the other form. In this form, the journals 20 and 23 of the paper supply roll and paper receiving roll, respectively, are mounted to slide freely in a single elongated bearing indicated by 107 which is 65 secured to the end plate or any fixed portion 66 of the machine by plates 108, 109 and 110. Between plates 109 and 110 the bearing is 70 provided with an opening 115 to permit the journals of the supply and receiving rolls to be passed through in inserting or removing them. Plate 110 is provided with an end piece 111 having a slot 112 which is 75 adapted to be engaged by a latch 113 pivoted to the bearing on the opposite side of the opening, as at 114. This latch closes the opening and prevents the rolls from coming out of the bearings whether the windings are large or small and also in transportation. In practice the latch is pivoted tightly so that it will not swing unless force is applied. 80

The left end of the machine as seen in Fig. 14 is the working end, that is the end at which the operating lever is placed and power is applied, and the power necessary to operate the feed roll is applied directly 85 instead of being transmitted, and applied at the other end of the feed shaft, as in the other form. This change enables me to lighten the weight of certain of the parts and to appreciably reduce the size and 90 weight of the machine, which is an important item both as regards the cost of production and the cost of transportation and handling in use.

Having thus described my invention I 95 claim:

1. In a mechanism of the character described, the combination with a feed roll partly around which an independent voting strip may pass, of a receiving roll whose winding rests upon the feed roll, a supply roll whose winding rests upon the winding of the receiving roll, clutch mechanism, a clutch shifter, a slide connected to the clutch shifter and a closing bar engaging the slide. 100
2. In a mechanism of the character described, the combination with a feed roll partly around which an independent voting strip may pass, of a receiving roll above the feed roll, a supply roll above the receiving roll, elongated bearings for the receiving and supply rolls which permit said rolls to move freely at right angles to the plane of rotation as the windings change, the entire weight of 105 said receiving and supply rolls and the windings thereon resting upon the feed roll, clutch mechanism, a clutch shifter, a slide connected to the clutch shifter and a closing bar engaging the slide. 110
3. In a mechanism of the character described, the combination with a feed roll partly around which an independent voting strip may pass, of a receiving roll whose winding rests upon the feed roll, a supply roll whose winding rests upon the winding of the receiving roll, a feed shaft which passes 115 through the feed roll without contact therewith, clutch mechanism intermediate the

feed shaft and the feed roll, a clutch shifter, a slide connected to the clutch shifter and a closing bar engaging the slide.

4. In a mechanism of the character described, the combination with a feed roll partly around which an independent voting strip may pass, a receiving roll above the feed roll and a supply roll above the receiving roll, of elongated bearings for the receiving and supply rolls which permit said rolls to move freely at right angles to the plane of rotation as the windings change, so that the entire weight of the receiving and supply rolls and the windings thereon is carried by the feed roll, a feed shaft passing through the feed roll without contact therewith, independent bearings for said feed roll and feed shaft, clutch mechanism, a clutch shifter, a slide connected to the clutch shifter and a closing bar engaging the slide.

5. In a mechanism of the character described, the combination with a feed roll having circumferential sets of holes, of toothed wheels mounted to rotate in mesh with said holes, a supply roll, a receiving roll which winds an independent voting strip after it has been indented or perforated by the toothed wheels, clutch mechanism, a clutch shifter, a slide connected to the clutch shifter and a closing bar engaging the slide.

6. In a mechanism of the character described, the combination with a feed roll partly around which an independent voting strip may pass, of a receiving roll above the feed roll, a supply roll above the receiving roll, a feed shaft passing through the feed roll without contact therewith, clutch members carried by the feed shaft and feed roll respectively, a clutch shifter, a slide connected to the clutch shifter and a closing bar engaging the slide.

7. In a mechanism of the character described, the combination with receiving and supply rolls and a feed roll partly around which an independent voting strip may pass and which is provided with circumferential series of holes, of toothed wheels registering with the holes in the feed roll whereby the independent voting strip is indented or perforated, clutch mechanism, a clutch shifter, a slide connected to the clutch shifter and a closing bar engaging the slide.

8. In a mechanism of the character described, the combination with an independent voting strip and a feed roll partly around which said strip passes and which is provided with circumferential series of holes, of toothed wheels mounted contiguous to the feed roll and meshing with the holes whereby the independent voting strip is indented or perforated, clutch mechanism, a clutch shifter, a slide connected to the clutch shifter and a closing bar engaging the slide.

9. An independent voting strip indicator

provided with means for registering with an independent voting strip and having a series of numerals corresponding with offices to be voted for and means for indicating divisions in the office line.

10. In a mechanism of the character described, the combination with a feed roll carrying a fixed clutch member, a feed shaft passing through the feed roll without contact therewith and a clutch sleeve carrying a clutch member and rotating with the feed shaft and sliding longitudinally thereon, of a clutch shifter engaging the clutch sleeve, a spring acting to retain the clutch shifter in operative position, a slide connected to the clutch shifter and a closing bar engaging the slide.

11. In a mechanism of the character described, the combination with a feed roll carrying a fixed clutch member, a feed shaft passing through the feed roll without contact therewith and a clutch sleeve carrying a clutch member and rotating with the feed shaft and sliding longitudinally thereon, of a clutch shifter, an actuating slide to which the clutch shifter is connected, a spring acting to retain the clutch shifter in operative position and a closing bar engaging the slide.

12. In a mechanism of the character described, the combination with a feed roll carrying a fixed clutch member, a feed shaft passing through the feed roll without contact therewith and a clutch sleeve carrying a clutch member and rotating with the feed shaft and sliding longitudinally thereon, of a clutch shifter, a slide to which the clutch shifter is connected and which is provided with an incline and a closing bar having a corresponding incline by which the slide is retracted.

13. In a mechanism of the character described, the combination with a feed roll carrying a fixed clutch member, a feed shaft passing through the feed roll without contact therewith and a clutch sleeve carrying a clutch member and rotating with the feed shaft and sliding longitudinally thereon, of a clutch shifter, a slide by which the clutch shifter is carried and which is provided with an incline, a closing bar having a corresponding incline by which the slide is retracted and the clutch members disengaged and means for actuating the slide in the opposite direction to engage the clutch members.

14. In a mechanism of the character described, the combination with supply, receiving and feed rolls, a feed shaft and clutch mechanism intermediate the feed roll and the feed shaft, of a front plate having an opening, a way plate having a recess, said opening and said recess comprising an incline and a land, a sliding shutter having an incline, an interlocking member, a link

- connected to said member and having a head lying in said opening and said recess and engaging said inclines, an actuating slide engaging said head and connections intermediate 5 the slide and the clutch mechanism, opening of the shutter acting to raise the link and force the head over on the land to lock the interlocking member, to actuate the slide and to engage the clutch mechanism, 10 and the return movement of the slide forcing the head off from the land and disengaging the clutch mechanism.
15. In a mechanism of the character described, the combination with a front plate having an opening, a way plate having a recess, said opening and said recess comprising an incline and a land and a sliding shutter having an incline, of an interlocking member, a link connected to said member 20 and having a head lying in said opening and said recess and engaging said inclines, and a slide engaging said head, substantially as described, for the purpose specified.
25. In a mechanism of the character described, the combination with a front plate having an opening, comprising an incline and a land and a sliding shutter having an incline, of a link having a head lying in said opening and engaging said inclines and a slide engaging 30 said head, substantially as described for the purpose specified.
35. In a mechanism of the character described, the combination with a front plate having an opening, comprising an incline and a land and a sliding shutter, of a link having a head lying in said opening and engaging said shutter and a slide engaging said head, substantially as described, for the purpose specified.
40. 18. In a mechanism of the character described, the combination with a front plate having an opening, comprising an incline and a land and a sliding shutter, of a link having a head which lies in said opening and engages the shutter and is provided with a widened lip, for the purpose set forth, and an actuating slide engaging said head.
45. 19. In a mechanism of the character described, the combination with a front plate having an opening comprising inclines 50 and 87 and a land, and a sliding shutter having an incline, of a link having a head lying in said opening and engaging the incline on the shutter and incline 87 and a slide engaging said head, opening of the shutter acting to raise the link and force the head over on the land and to actuate the slide, the return movement of the slide forcing the head off from the land and incline 70 forcing it downward into the opening.
55. 20. In a mechanism of the character described, the combination with a front plate having an opening, comprising an incline and a land and a sliding shutter, of a link having a head which lies in said opening and engages the shutter and a slide having an engaging wall which is engaged by said head to actuate the slide and on the return movement forces the head off from the land.
60. 21. In a mechanism of the character described, the combination with a front plate having an opening, comprising an incline and a land and a sliding shutter, of a link having a head which lies in said opening and engages the shutter, a slide having a wall engaged by said head when the shutter is opened and means for returning the slide and forcing the head off from the land.
65. 22. In a mechanism of the character described, the combination with a front plate having an opening, comprising an incline and a land and a sliding shutter, of a link having a head lying in said opening and engaging the shutter, a slide engaging said head for the purpose set forth and a closing bar engaging the slide to produce the return movement.
70. 23. In a mechanism of the character described, the combination with a feed shaft, a closing bar and connections intermediate said shaft and said bar, of a front plate having an opening comprising an incline and a land, a sliding shutter, a link having a head lying in said opening and engaging the shutter, a slide engaged by said head and actuated when the shutter is opened and connections intermediate the closing bar and the slide whereby the latter is returned when the feed shaft is actuated.
75. 24. In a mechanism of the character described, the combination with a feed roll and a feed shaft which passes through the feed roll without contact therewith, of bearings for the feed shaft, bearings for the feed roll whereby the latter is supported without weight on the feed shaft, clutch mechanism intermediate said roll and the shaft, a clutch shifter, a slide connected to the clutch shifter and a closing bar engaging the slide.
80. 25. In a mechanism of the character described, the combination with a feed roll, a feed shaft, bearings for the feed shaft, independent bearings for the feed roll and clutch mechanism intermediate said shaft and said roll, of a slide by which the clutch mechanism is operated, a sliding shutter, intermediate connections by which the slide is actuated to engage the clutch members and a closing bar actuated by the feed shaft whereby the slide is actuated to disengage the clutch member.
85. 26. In a mechanism of the character described, the combination with a feed roll, a feed shaft, bearings for the feed shaft, independent bearings for the feed roll and clutch mechanism intermediate said shaft and said roll, of a slide by which the clutch mechanism is operated, a sliding shutter, a front plate having an opening comprising

- an incline and a land, a link having a head lying in said opening and engaging the shutter, the head being forced upon the land, the slide actuated and the clutch members engaged by the opening of a shutter, and means actuated by the feed shaft for returning the slide.
27. In a mechanism of the character described, the combination with a feed roll, a feed shaft, clutch mechanism intermediate said roll and said shaft, a slide by which said clutch mechanism is operated, and a sliding shutter, of a front plate having an opening and a link having a head lying in said opening and engaging the shutter, said slide being actuated and the clutch members engaged by the opening of the shutter.
28. In a mechanism of the character described, the combination with a feed shaft, a closing bar and intermediate connections, of a slide, engaging inclines on said slide and bar, a front plate having an opening, a sliding shutter and a link having a head lying in said opening and adapted to engage the slide, the opening of a shutter raising the link and actuating the slide.
29. In a mechanism of the character described, the combination with a closing bar, an actuating slide and engaging inclines on said bar and slide, of a front plate having an opening comprising an incline and a land, a sliding shutter having an incline and a link having a head engaging said inclines, opening of the shutter forcing the head upon the land and actuating the slide.
30. In a mechanism of the character described, the combination with a feed roll, a loosely-journalized receiving roll resting upon the feed roll and a loosely-journalized supply roll resting upon the receiving roll, of swinging hooks pivoted above the journals of the supply roll and adapted to be displaced by said journals when the supply roll is raised and to then drop back and support the supply roll so that the receiving roll may be removed, clutch mechanism, a clutch shifter, a slide connected to the clutch shifter and a closing bar engaging the slide.
31. In a mechanism of the character described, the combination with a feed roll, of a receiving roll resting upon the feed roll and loosely journalized to permit movement in a plane transverse to the plane of rotation, a supply roll resting upon the receiving roll and also loosely journalized to permit movement in a plane transverse to the plane of rotation, clutch mechanism, a clutch shifter, a slide connected to the clutch shifter and a closing bar engaging the slide.
32. In a mechanism of the character described, the combination with a feed roll, of a receiving roll resting upon the feed roll and loosely journalized to permit movement in a plane transverse to the plane of rotation, a supply roll resting upon the receiving

tion, a supply roll resting upon the receiving roll and also loosely journalized to permit movement in a plane transverse to the plane of rotation and means for holding the supply roll suspended to permit removal of the receiving roll.

33. In a mechanism of the character described, the combination with a front plate having an opening comprising an incline and a land, way plates having guard flanges for the purpose set forth, and a shutter sliding in the way plates, of a link having a head lying in said opening which when raised by the shutter engages said incline and land and a slide engaging said head.
34. In a mechanism of the character described, the combination with an independent voting strip having series of perforations or indentations, of a voting strip indicator having cross lines adapted to register with said perforations or indentations, numerals corresponding with the offices to be voted for and means for indicating the divisions of the office line.

35. In a mechanism of the character described, the combination with a feed roll carrying a fixed clutch member, a feed shaft passing through the feed roll and clutch members carried by said shaft and roll, of a clutch shifter, an actuating slide, a U-shaped bracket carried thereby, a removable pin passing through said bracket and the clutch shifter, a spring bearing against the clutch shifter and a closing bar engaging the slide.

36. In a mechanism of the character described, the combination with a front plate having an opening comprising an incline and a land and a sliding shutter, of a link having a head lying in said opening which when raised by the shutter engages said incline and land, said head being provided with a lip engaging the front plate to retain the head in position.

37. In a mechanism of the character described, the combination with a feed roll partly around which an independent voting strip may pass, of receiving and supply rolls, elongated bearings in which the journals of the receiving and supply rolls slide freely and in alignment, clutch mechanism, a clutch shifter, a slide connected to the clutch shifter and a closing bar engaging the slide.

38. In a mechanism of the character described, the combination with a feed roll partly around which an independent voting strip may pass, of receiving and supply rolls, elongated bearings in which the journals of the receiving and supply rolls slide freely and which are provided with openings for the journals to pass, latches adapted to close said openings, clutch mechanism, a clutch shifter, a slide connected to the clutch shifter and a closing bar engaging the slide.

39. In a mechanism of the character described, the combination with a feed roll partly around which an independent voting strip may pass, of receiving and supply 5 rolls, elongated bearings in which the journals of the receiving and supply rolls slide freely and which are provided with openings for the journals to pass, plates by which the bearings are secured in place, 10 one plate of each bearing having a slotted

end piece, and latches pivoted on the other sides of the openings and engaging the slots to retain the rolls in place.

In testimony whereof I affix my signature, in presence of two witnesses.

CHARLES C. ABBOTT.
